Patented Sept. 5, 1916.

UNITED STATES PATENT OFFICE.

WILL CRUZEN, OF ST. PAUL, MINNESOTA.

PROTRACTOR.

1,197,268.

Specification of Letters Patent.

Patented Sept. 5, 1916.

Application filed February 28, 1916. Serial No. 80,998.

To all whom it may concern:

Be it known that I, WILL CRUZEN, a citizen of the United States, residing at St. Paul, in the county of Ramsey and State of Minnesota, have invented a new and useful Protractor, of which the following is a specification.

The present invention appertains to protractors, and aims to provide an instrument 10 of that character of novel and improved construction, which is applicable to the blade of a T-square, to be adjusted longitudinally thereon and having an arm adapted to be set at various angles, whereby the present 15 device can be used in lieu of the ordinary protractor and triangles.

One of the objects of the invention is the provision of unique means for applying the device to the blades of T-squares of various 20 widths.

This instrument in being removable from the T-square enables the T-square to be used without the instrument in the ordinary manner so that two T-squares are not necessary. The instrument is also adapted to hold varicus rules or blades, such as engineers' and architects' rules, etc.

Another object of the invention is to provide a novel assemblance of the component 30 elements of the protractor, to enhance the utility and efficiency thereof.

It is also within the scope of the invention to provide a protractor having the characteristics above noted, and which at the same 35 time is comparatively simple and inexpensive in construction, as well as being practical and serviceable in use.

With the foregoing and other objects in view which will appear as the description 40 proceeds, the invention resides in the combination and arrangement of parts and in the details of construction hereinafter described and claimed, it being understood that changes in the precise embodiment of the 45 invention herein disclosed, can be made within the scope of what is claimed, without departing from the spirit of the invention.

The invention is illustrated in the accompanying drawing, wherein:—

Figure 1 is a plan view of the instrument as applied to the blade of a T-square, portions being broken away. Figs. 2, 3, 4 and 5 are sectional details taken on the lines 2—2, 3—3, 4—4 and 5—5, respectively, of Fig. 1.

In carrying out the invention, the instrument embodies a rectangular plate 1 adapted to rest upon the blade 2 of a T-square, and having at one end a downwardly offset 60 approximately semi-circular protractor stock or wing 3 forming a shoulder 4 to seat against the adjacent edge of the blade 2. A second plate 5 rests upon the plate 1 and is provided at that end remote from the stock 65 3 with an angularly extending flange or lip 6 to seat against the opposite edge of the blade 2, whereby the blade can be clamped between the shoulder 4 and flange 6 to hold the instrument in position.

In order to adjustably connect the plates 1 and 5 whereby they can be applied to blades of various widths, the upper plate 5 is provided with a longitudinal slot 7, and a clamping bolt 8 extends through the slot and 75 has a countersunk head seated in the lower plate 1. A nut 8^a is threaded on the bolt 8 and a washer 9 seats upon the plate 5 around the bolt 8 under the nut, in order that when the nut is tightened, the plate 5 will be effectively forced tightly upon the plate 1. The plate 5 which is thicker than the plate 1 is provided with a lower longitudinal dove-tailed recess 10 in which the plate 1 is 80 slideable, said plate 1 being of dove-tailed cross section, whereby the two plates will be held 85 assembled for longitudinal adjustment only relative to one another.

The plate 1 is provided at that end adjacent the stock 3 with a dove-tailed recess 11 90 extending away from the stock 3, and a plate 12, which may be of celluloid or other transparent material, has a portion of dove-tailed cross section fitting snugly within the recess 11 to assemble the plate 12 with the 95 plate 1 under the plate 5. The plate 12 projects from the plate 1 parallel with the stock 3, and a radial arm 13 has its inner end disposed snugly between the plate 12 and stock 3, and a bolt 14 is engaged through the plate 100 12, arm 13, and stock 3 to pivot the arm 13 to the stock and has a countersunk head seated in the stock 3 and upper nut 14^a. The free end of the arm 13 is provided with a head 15 slidably fitting the curved edge of 105 the stock 3, and a radial strip 16 has its inner end engaged with the bolt 14 upon the plate 12 under the nut 14^a, and has its free end engaged with a bolt 17 having a lower countersunk head seated in the arm 13 and 110 an upper nut 17^a upon the strip 16. When the nut 17^a is tightened it forces the strip 16

downward and clamps the plate 12 between the arm 13 and strip 16 to hold the arm 13 in place.

In order to indicate the angle of the arm 13, said arm is provided adjacent its free end with an aperture 18, and the stock 3 is provided along its curved edge with two sets of oppositely reading degree or protractor graduations 19 which are exposed through 10 the aperture 18, and a magnifying glass or lens 20 is secured within the aperture 18, and has upon its lower surface a hair line or scratch 21 serving as a pointer coöperable with the graduations 19. The magnifying 15 glass enables the graduations to be readily read, and provides for an accurate adjustment.

The head 15 is provided at its outer end with a slot or recess 22 receiving the inner 20 end of a radial ruler or blade 23, which is secured in place by means of a bolt 25 and its nut 26 as seen in Fig 5. Various rulers or blades can be used interchangeably.

The present instrument can be readily applied to various T-squares, and can be adjusted longitudinally upon the blade to which it is applied. The blade 26 can be readily adjusted to the desired angle, whereby the present instrument can be used in 30 place of the ordinary triangles and protractors now used, the present device being less troublesome and more serviceable. The construction of the device is comparatively simple but this does not depreciate the utility 35 of the instrument. The instrument can be used by draftsmen and other artisans as will of course be apparent.

Having thus described the invention, what is claimed as new is:—

40 1. A protractor embodying a plate having a downwardly offset graduated protractor stock at one end forming a shoulder to engage one edge of a blade, a second plate having a recess in which the first mentioned 45 plate is slidable and having a flange remote from said stock to engage the opposite edge of the blade, means for clamping said plates

together at various adjustments thereof, said plates being slidable longitudinally relative to one another when they are loosened, and 50 a radial arm pivoted to said stock.

2. A protractor embodying a plate having a downwardly offset graduated protractor stock forming a shoulder to rest against the edge of a blade upon which said plate rests, 55 said plate having a recess adjacent said stock, a second plate fitting in said recess and projecting therefrom, a radial arm having its inner end disposed between said stock and second plate, and a pivot engaging 60 through said plates and arm.

3. A protractor embodying a plate to rest on a blade and having a downwardly offset graduated protractor stock at one end forming a shoulder to rest against one edge of 65 said blade, a second plate resting upon the first mentioned plate and having a flange remote from said stock to rest against the other edge of said blade, means adjustably connecting said plates for clamping them together, the first mentioned plate having a recess adjacent said stock, a third plate fitting in said recess and projecting therefrom, a radial arm coöperable with said stock and projecting under the third plate, 70 and a pivot engaged through the first mentioned and third plates and said arm.

4. A protractor embodying a plate having a graduated stock, a second plate assembled with said plate and projecting over the 80 stock, a radial arm between said stock and second plate, a pivot engaging said arm, stock and second plate, a strip upon the second plate engaging the pivot, and means connecting said strip and arm to clamp the 85 second plate between them.

In testimony that I claim the foregoing as my own, I have hereto affixed my signature in the presence of two witnesses.

WILL CRUZEN.

Witnesses:

T. A. ALEXANDER,
JAMES VERRILL.
